UNITED STATES PATENT OFFICE.

HUGH MCKENNA AND GEORGE D. BULMER, OF PENN, ALLEGHENY COUNTY,
ASSIGNORS TO BOOTH & FLINN, OF PITTSBURG, PENNSYLVANIA.

PIPE-JOINT.

SPECIFICATION forming part of Letters Patent No. 319,289, dated June 2, 1885.

Application filed April 27, 1885. (No model.)

To all whom it may concern:

Be it known that we, HUGH MCKENNA and GEORGE D. BULMER, of Penn township, in the county of Allegheny and State of Pennsylvania, have invented a new and useful Improvement in Devices for Making the Joints of Natural-Gas Pipes; and we do hereby declare the following to be a full, clear, and exact description thereof, reference being had 10 to the accompanying drawings, in which—

Figure 1 is a perspective view of a joint illustrating the use of our improvement. Fig. 2 is a longitudinal section of the same. Figs. 3 and 4 are side and edge views of the elastic 15 ring.

Like letters of reference indicate like parts.

In forming the joints of natural-gas conductors in which tongue-and-socket pipe-sections are used it has been customary to make 20 the tongue end of a pipe-section with an external bead and the bowl end with a large socket so as to receive the bead and form an annular recess around the inserted tongue end of the next section. In natural-gas conductors it is desirable that the joints be closed 25 by a packing of lead poured into the annular recess. In order to accomplish this pouring, the tongue end of the pipe-section is first entered into the bowl end of the next section, 30 and a ring of clay or other material is placed around the inserted pipe at the end of the receiving-pipe, with a lateral pouring-hole on the upper side. This ring forms the fourth side of the annular recess, and retains the lead 35 in position at the end of the receiving-pipe until it becomes set in the joint. Among other devices used for this purpose has been a flexible ring of steel, having an inner facing 40 of packing material, which embraced the inserted pipe and was drawn tightly around the same by means of a clamping-screw attached by hooks or other devices to its ends. The objection to this device was that it was liable 45 to become misshapen and not fit perfectly in the mouth of the bowl, and the clamping-screw arrangement was unhandy and troublesome. By our invention these difficulties are all obviated, and the cost of the appliance is very much reduced.

50 In the drawings, *a* represents the receiving-

pipe, and *b* the inserted pipe. *c* is the bead on the end of the inserted pipe; *d*, the bowl of the receiving-pipe, and *e* the annular recess formed by the bowl around the end of the inserted pipe.

We make a thick annulus of india-rubber, *f*, cut at one side, as at *f'*, and to the ends thus formed we attach, by rivets or otherwise, hooks *g*. This annulus is placed around the inserted pipe *b*, against the end of the bowl *d*, so as to form a fourth side of the recess *e*. The two ends are brought near together, the annulus being tightly stretched on the pipe *b* by means of a pair of tongs, *h*, provided with securing-bar *i*.

60 The opening *f'* forms a pouring-gate, through which the molten lead can be poured into the annular recess *e*, the outer side of the pouring-gate being formed by a lump or wad of clay, *j*.

65 The annulus *f*, being composed entirely of one integral body of very elastic material, conforms itself exactly to the surface of the pipe *b*, making a perfectly-tight joint, and not exposed to distortion, as in the case of the 70 steel ring before mentioned.

The device is cheap and simple. The tongs *h* are also cheap in construction, easily used, and not in the way.

75 The whole apparatus facilitates the laying 80 of the pipe and effects a saving of time.

What we claim as our invention, and desire to secure by Letters Patent, is—

1. The combination of the pipe *a* *b*, rubber ring *f*, provided with hooks *g*, and the tongs 85 *h*, substantially as and for the purposes described.

2. A device for closing the bowl end of pipes, for the purpose specified, consisting of the rubber ring *f*, provided with hooks *g*, in 90 combination with the tongs *h*, substantially as and for the purposes described.

In testimony whereof we have hereunto set our hands this 11th day of April, A. D. 1885.

HUGH MCKENNA.
GEORGE D. BULMER.
